LIQUID FUEL BURNER

John F. Harvey, Akron, and Arthur W. Hermendorfer, Barberton, Ohio, assignors to The Babcock & Wilcox Company, Newark, N. J., a corporation of New Jersey

Application February 28, 1940, Serial No. 321,192

13 Claims. (Cl. 299—120)

This invention relates to the construction and operation of liquid fuel burners, and more particularly to variable capacity pressure atomizing liquid fuel burners of the return flow type in which the liquid fuel is supplied through an inner barrel and the return flow is through an annular passage formed between the inner and outer barrels.

Mechanical atomizing liquid fuel burners in which the liquid fuel is delivered to a circular whirling chamber under pressure through substantially tangentially arranged slots are well known. The liquid fuel passes through the whirling chamber in a spiral path due to the conversion of its supply pressure into angular and axial velocities and is discharged from an end orifice in a hollow cone shaped spray, the angle of the spray being determined by the angular and axial velocities of the liquid fuel as discharged.

The three important operating features of a liquid fuel burner of this type, particularly when intended for marine use, are its range of capacity, variation in spray angle, and quality of atomization. Since the quantity of oil passing through the discharge orifice varies substantially as the square root of the supply pressure, the maximum variation in capacity with no change in size of the discharge orifice is inherently low within practical limits of supply pressure and effective atomization, and in the ratio of not over 2:1. A constant spray angle is highly desirable to insure complete and efficient combustion at all capacities by precluding the danger of furnace wall carbonization or furnace hot spots. It has been found that the spray angle tends to decrease as the amount of liquid fuel discharged from the discharge orifice increases. A fine quality of atomization under all operating conditions is essential to insure rapid, uniform and complete vaporization and combustion.

A greater range of capacity is attainable with liquid fuel burners of the return flow type in which a variable portion of the liquid fuel supplied to the burner can be by-passed through a return flow passage in the burner to vary the amount discharged through the discharge orifice. The amount of by-passed fuel is dependent on the pressure in the return flow passage and a control valve is usually located therein for this purpose. The liquid fuel return passage is connected to a fuel reservoir or inlet side of a feed pump. The wider range of capacities attainable in burners of this type is however frequently at

the expense of the quality of atomization or spray angle variation.

The main object of the invention is the provision of an improved construction of the parts forming the discharge end of a liquid fuel burner of the return flow type whereby the burner will be characterized in operation by improved atomization conditions over a wide range of capacities and particularly by fine atomization and a relatively small variation in spray angle over the desired range of capacities. Further and more specific objects are an improved location of the return flow connection to the main path of liquid fuel flow and an improved construction of the parts defining the connection.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described preferred embodiments of our invention.

Of the drawings:

Fig. 1 is an elevation, partly in section and broken along its length, of a liquid fuel burner constructed in accordance with our invention;

30 Fig. 2 is a section taken on the line 2—2 of Fig. 1;

Fig. 3 is an enlarged view of the burner tip parts shown in Fig. 1;

35 Fig. 4 is a section taken on the line 4—4 of Fig. 3, showing the furnace face of the primary nozzle;

Fig. 5 is a section taken on the line 5—5 of Fig. 3, showing the furnace face of the secondary nozzle;

40 Fig. 6 is a section taken on the line 6—6 of Fig. 3, showing the outer face of the sprayer plate;

Fig. 7 is a view similar to Fig. 3 illustrating a modified tip construction;

45 Fig. 8 is a section similar to Fig. 5 taken on the line 8—8 of Fig. 7; and

Fig. 9 is a section taken on the line 9—9 of Fig. 7 showing the outer face of the secondary nozzle.

50 In the liquid fuel burner illustrated in Figs. 1—6, the atomizing parts are arranged within a horizontally arranged tube or distance piece 10 having its furnace, forward, or discharge end flaring carrying thereon an impeller plate 11 which is normally positioned in a fuel burner port of

the furnace wall. The outer end of the distance piece is threaded into a coupling 12 in which is formed a pair of parallel passages 13 and 14 serving as the liquid fuel supply and return flow passages respectively. The coupling passages are detachably connected to corresponding passages 15 and 16 in a body member 17 by a coupling yoke 18 adapted to be held in its closing position by a T-handle set screw 19. The upper end of the supply passage 15 opens into the outer end of a supply passage 20 formed by an elongated inner barrel or supply tube 21 threaded into the atomizer body, while the upper end of the return flow passage 16 is connected to the outer end of an annular passage 22 formed by the tube 21 and an outer barrel or tube 23 having a slip joint connection with the body 17. With this arrangement the fuel supply passage 20 is separated from and surrounded by the annular return flow passage 22.

The passage 20 is of uniform internal diameter throughout its length and the furnace end of the tube 21 is threaded to engage a cylindrical primary nozzle or plug member 24 having a sealing contact with the furnace end of the tubes 21 and 23. As shown in Figs. 3 and 4, the primary nozzle 24 has an annular slot 25 formed in its furnace face which is connected to the supply passage 20 by a circular series of diverging passages 26. The primary nozzle also has an annular slot 27 in its furnace face of larger diameter and concentric with the slot 25. The slot 27 is connected with the annular return flow passage 22 by a circular series of small passages 28 arranged parallel to the axis of the primary nozzle.

The furnace face of the primary nozzle 24 when assembled contacts with the outer face of a secondary nozzle or inner tip member 30 having a cylindrical central passage therethrough which constitutes the outer portion of a mixing or whirl chamber 32, the outer end of which is closed by the imperforate portion of the furnace face of the primary nozzle. A series of symmetrical slots 33 is formed in the outer face of the secondary nozzle in position to receive liquid fuel from the annular slot 25 and deliver the same substantially tangentially into the outer end of the whirl chamber 32. An annular slot 35 is formed in the furnace face of the secondary nozzle in alignment with the slot 27 of the primary nozzle and connected thereto by short passages 36.

The furnace face of the secondary nozzle beyond the slot 35 contacts with the outer face of a sprayer or orifice plate or outer tip 38 which has a portion of its periphery cut away to provide a seat for an end cap 39 which is screwed on the outer tube 23 to hold the primary nozzle, secondary nozzle, and sprayer plate in their desired assembled position. The sprayer plate has a central cylindrical opening 40, which is in alignment with and forms a continuation of the whirl chamber 32 and at its furnace end discharges through an orifice 41 of substantially smaller diameter than the whirl chamber.

With the foregoing construction the liquid fuel, preferably heated oil under a substantial pressure, e. g. 200 lbs. per sq. in., is delivered through the passages 13 and 15 to the supply passage 20 from which it passes through the holes 26, annular slot 25, and tangential slots 33 into the outer end of the whirl chamber 32. Due to the tangential arrangement of the slots 33 the oil follows a spiral path in the whirl chamber toward the discharge orifice 41.

In liquid fuel atomizing burners of the return

flow type heretofore proposed, provisions are made for by-passing a variable portion of the oil supplied back to the fuel reservoir or feed pump for the purpose of varying the burner capacity. The control is effected by means of a valve in the return flow line to vary the pressure therein and thereby the quantity of oil by-passed. As the valve is opened the pressure in the return line will drop and the amount of fuel returned will be proportionately increased. In such constructions the sprayer plate is supplemented by a second orifice plate spaced from the furnace end of the sprayer plate to provide a space therebetween connected to the return flow line. The connection of the return by-pass to the furnace side of the discharge orifice appears to create frictional and other disturbances which cause relatively coarse atomization of the fuel discharged into the furnace over a major portion of its designed capacity range and a relatively large variation in spray angle with changes in capacity.

In the present construction, the portion of the fuel by-passed is advantageously removed from the stream moving toward the furnace at a point on the peripheral wall of the whirl chamber, and preferably about midway between the point of entrance of the supply slots 33 and the discharge orifice 41. As shown in Figs. 3 and 6 the outer face of the sprayer plate 38 is cut away to form a circular recess 45 over most of its area, the outer periphery of the recess registering with the outer side of the annular slot 35 of the secondary nozzle. This construction results in an annular opening or orifice in the wall of the whirl chamber midway of its length. In operation, the resultant effect may be visualized as the continuous removal of a circular lamina or portion of the fuel stream passing through the whirl chamber, whereby a drop in the whirl chamber pressure will result. The resultant pressure drop will cause an increase in the quantity of fuel entering the whirl chamber due to the increase in the pressure differential across the inlet orifice and some decrease in the axial velocity at the discharge orifice. The angular velocity at the discharge orifice is little affected, hence, the spray angle will be slightly increased.

It has been found desirable to construct the parts forming the liquid fuel passage in certain proportions for optimum operation. In particular, the total cross-sectional flow area of the supply slots 33 is approximately one and one-half times the flow area of the discharge orifice 41, while the flow area of the return orifice into the space 45 is substantially greater than the area of the slots 33. The remaining portion of the liquid fuel stream continues in a spiral path through the remaining portion of the whirl chamber and is discharged through the discharge orifice 41.

The described burner tip construction has been found to result in the production of a relatively fine spray throughout a capacity range of more than 7:1, and also to result in a relatively small variation in the spray angle throughout this range with consequent substantially uniform flame conditions in the associated furnace.

In the modified construction illustrated in Figs. 7-9 the burner parts are similarly constructed except that the oil return connection is formed by substantially tangential slots 50 formed in the furnace face of the secondary nozzle rather than the recess 45 in the outer face of the sprayer plate. In both constructions the liquid fuel is substantially tangentially supplied to an elong-

gated whirl chamber and a variable portion withdrawn through a return passage opening to an intermediate peripheral portion of the whirl chamber.

It will be noted that either return flow burner construction described can be readily converted into a straight mechanical atomizing fuel burner by replacing only one part. In the Figs. 1-6 construction, a sprayer plate without the recess 45 will accomplish this result, while in the Figs. 7-9 construction, a secondary nozzle member without the slots 50 is all that is required for this purpose.

While in accordance with the provisions of the statutes we have illustrated and described here- 10 in the best forms of the invention now known to us, those skilled in the art will understand that changes may be made in the form of the apparatus disclosed without departing from the spirit of the invention covered by our claims, 15 and that certain features of our invention may sometimes be used to advantage without a corresponding use of other features.

We claim:

1. A return flow liquid fuel burner comprising 25 an inner liquid fuel supply tube, an outer tube forming a return flow passage therebetween, a nozzle member at one end of said inner and outer tubes and having a central whirl chamber of circular cross-section, a liquid fuel inlet passage connected to said supply tube and substantially tangentially connected to one end of said whirl chamber, a sprayer plate contacting with said nozzle member and having an opening therein forming part of said whirl chamber and a discharge orifice at the opposite end of said opening, the contacting face of said nozzle member being constructed to define a return flow slot having a substantially tangential connection at one end to said whirl chamber intermediate the length of said whirl chamber and its other end connected to said return flow passage.

2. An atomizer for a burner barrel having concentric supply and return passages, comprising 45 a plug adapted to be fitted to the end of said barrel and to form an end closure for said passages, an inner tip seated against said plug and having a central chamber therein, an annular set of tangential inlet passages for said chamber, an annular set of return passages in said 50 inner tip concentric with said set of inlet passages, and outer tip seated on said inner tip and having a chamber registering with and forming a continuation of said first chamber and terminating forwardly in a discharge orifice, said outer tip being spaced from said inner tip to form a return passage from said chambers to said first mentioned return passages, and concentric sets of supply and return passages in said plug connecting the supply and return passages of said 60 barrel to the inlet and return passages respectively of the inner tip.

3. An atomizer for a burner barrel having concentric supply and return passages, comprising a plug adapted to be fitted to the end of said barrel and to form an end closure for said passages, an inner tip seated against said plug and having a central chamber therein, a set of substantially tangential inlet passages for said chamber, a set of return passages in said inner tip surrounding said set of inlet passages, an outer tip seated on said inner tip and having a chamber registering with and forming a continuation of said first chamber and terminating forwardly in a discharge orifice, the adjacent surface portions of 75

said inner and outer tips being formed to define therebetween a return flow connection from said chambers to said first mentioned return passages, and sets of supply and return passages in said 10 plug connecting the supply and return passages of said barrel to the inlet and return passages respectively of the inner tip.

4. An atomizer for a burner barrel having concentric supply and return passages, comprising a 15 plug adapted to be fitted to the end of said barrel and to form an end closure for said passages, an inner tip seated against said plug and having a central chamber therein, a plurality of substantially tangential inlet passages for said chamber, a plurality of return passages in said inner tip surrounding said inlet passages, an outer tip seated on said inner tip and having a chamber registering with and forming a continuation of said first chamber and terminating forwardly in a discharge orifice, the adjacent surface portions of said inner and outer tips being formed to define therebetween a return flow connection of substantially greater flow area than the total flow area of said inlet passages, said return flow connection extending from said chambers to said first mentioned return passages, concentric supply and return passages in said plug connecting the supply and return passages of said barrel to the inlet and return passages respectively of the inner tip, and a cap attached to said barrel having an inner peripheral flange arranged to center and secure said tips in position.

5. A return flow liquid fuel burner having 20 means forming a whirl chamber of circular cross-section and an axial length at least equal to its diameter, means forming a substantially tangentially arranged liquid fuel inlet at one end of said whirl chamber, a discharge orifice at the opposite end of said whirl chamber, and means 25 for removing a peripheral portion of the whirling liquid fuel in said whirl chamber comprising a circular set of return flow passages surrounding and connected to peripheral portions of said whirl chamber intermediate the length thereof, said whirl chamber being of uniform circular cross-section from its fuel inlet end to a point axially spaced beyond said return flow passage connection thereto.

6. A return flow liquid fuel burner having 30 means forming a whirl chamber of circular cross-section and greater axial length than diameter, a discharge orifice at one end of said whirl chamber, means forming a substantially tangentially arranged liquid fuel inlet at the opposite end of said whirl chamber, and means for removing a peripheral portion of the whirling liquid fuel in said whirl chamber comprising a return flow passage opening to said whirl chamber throughout the circumference and intermediate the length thereof, said whirl chamber being of uniform circular cross-section from its fuel inlet end to a point axially spaced beyond said return flow passage connection thereto.

7. A return flow liquid fuel burner having 35 means forming an axially elongated whirl chamber of circular cross-section, means forming a substantially tangentially arranged liquid fuel inlet at one end of said whirl chamber and terminating at the entrance thereto, a discharge orifice at the opposite end of said whirl chamber, and means for removing a peripheral portion of the whirling liquid fuel in said whirl chamber comprising a circular set of return flow 40 passages surrounding and connected to peripheral portions of said whirl chamber approxi-

mately midway of the length thereof, said whirl chamber being of uniform circular cross-section from its fuel inlet end to at least the forward wall of said return flow passage connection thereto.

8. A return flow liquid fuel burner having means forming a whirl chamber of circular cross-section and greater axial length than diameter, means forming a substantially tangentially arranged liquid fuel inlet at one end of said whirl chamber and terminating at the entrance thereto, a discharge orifice at the opposite end of said whirl chamber, and means for removing a peripheral portion of the liquid fuel whirling in said whirl chamber comprising a circular set of return flow passages substantially tangentially arranged relative to and opening to said whirl chamber intermediate the length thereof, said whirl chamber being of uniform circular cross-section from its fuel inlet end to at least the points of connection of said return flow passages thereto.

9. A return flow liquid fuel burner comprising an inner liquid fuel supply tube, an outer tube forming a return flow passage therebetween, means at one end of said inner and outer tubes defining a central whirl chamber of circular cross-section, a liquid fuel inlet passage connected to said supply tube and substantially tangentially connected to one end of said whirl chamber, a discharge orifice at the opposite end of said whirl chamber, means defining a circular set of return flow passages surrounding and connected at one end to peripheral portions of said whirl chamber intermediate the length thereof and at their other end to said return flow passage, said whirl chamber being of uniform circular cross-section from its fuel inlet end to a point axially spaced beyond the points of connection of said return flow passages thereto.

10. An atomizer for a burner barrel having concentric supply and return passages, comprising a plug adapted to be fitted to the end of said barrel and to form an end closure for said passages, a burner tip structure seated against said plug and having a central whirl chamber of circular cross-section therein of an axial length at least equal to its diameter and terminating forwardly in a discharge orifice, a plurality of substantially tangential inlet passages for said whirl chamber terminating at the periphery thereof, a circular set of return passages in said tip structure forming a return flow connection from intermediate peripheral portions of said whirl chamber rearwardly of said discharge orifice to said first mentioned return passage, and concentric supply and return passages in said plug connecting the supply and return passages of said barrel to the inlet and return passages respectively of said tip structure, said whirl chamber being of uniform circular cross-section from said inlet passages to at least the forward wall of said return flow connection.

11. A return flow liquid fuel burner comprising an inner liquid fuel supply tube, an outer tube forming a return flow passage therebe-

tween, a nozzle member at one end of said inner and outer tubes and having a central whirl chamber of circular cross-section, a liquid fuel inlet passage connecting said supply tube to and substantially tangentially opening into one end of said whirl chamber, a sprayer plate contacting with said nozzle member and having an opening therein forming part of said whirl chamber and a discharge orifice at the opposite end of said opening, the adjacent portions of said sprayer plate and nozzle member being constructed and arranged to define a return flow connection opening at one end over a substantial peripheral portion of said whirl chamber intermediate the length of said whirl chamber and at its other end to said return flow passage, said whirl chamber being of uniform circular cross-section from its fuel inlet end to a point axially spaced beyond said return flow connection thereto.

12. A return flow liquid fuel burner comprising an inner liquid fuel supply tube, an outer tube forming a return flow passage therebetween, a nozzle member at one end of said inner and outer tubes and having a central whirl chamber of circular cross-section, a liquid fuel inlet passage connected to said supply tube and substantially tangentially opening into one end of said whirl chamber, a sprayer plate contacting with said nozzle member and having an opening therein forming part of said whirl chamber and a discharge orifice at the opposite end of said opening, the contacting face of said sprayer plate being recessed and arranged to define a return flow connection opening at one end over a substantial peripheral portion of said whirl chamber intermediate the length of said whirl chamber and at its other end to said return flow passage, said whirl chamber being of uniform circular cross-section from its fuel inlet end to a point axially spaced beyond said return flow connection thereto.

13. A return flow liquid fuel burner comprising an inner liquid fuel supply tube, an outer tube forming a return flow passage therebetween, a nozzle member at one end of said inner and outer tubes and having a central whirl chamber of circular cross-section, a liquid fuel inlet passage connected at one end to said supply tube and substantially tangentially opening at its opposite end into one end of said whirl chamber, a sprayer plate contacting with said nozzle member and having an opening therein forming part of said whirl chamber and a discharge orifice at the opposite end of said opening, the contacting face of said sprayer plate having a circular recess arranged to define an annular return flow passage surrounding and opening at its center to a circumferential section of said whirl chamber intermediate the length of said whirl chamber and at its outer periphery to said return flow passage, said whirl chamber being of uniform circular cross-section from its fuel inlet end to a point axially spaced beyond said return flow connection thereto.
